UNITED STATES PATENT OFFICE.

LOUIS KEITH MORRISON, OF DECATUR, GEORGIA.

ADJUSTABLE GARTER.

Application filed May 28, 1927. Serial No. 194,955.

This invention relates to improvements in adjustable garters.

An object of this invention is to provide a garter having an adjustment both circumferentially and longitudinally of the leg.

The feature of prime importance in this application is the means whereby the garter may be adjusted according to the length of the leg, as well as to the length of the sock 10 or stocking.

Other objects of this invention will appear from the following detailed description of the device and as disclosed in the single sheet of drawings which is herewith 15 made a part of this application.

In the drawings—

Figure 1 illustrates a perspective view of the adjustable garter.

Figure 2 represents a sectional view of 20 the longitudinal adjustable feature, taken along line 2—2 of Figure 1.

Numerical 1 designates the circumferential portion of the garter ordinarily made from a material having a suitable elasticity and 25 provided with an adjustment element 2, and a cooperating element 3 for detachably connecting with the opposite end of the garter as at 4. One end of the garter strap 1 is provided with a tab portion 5 integrally attached thereto by means of threads or otherwise as at 6, the tab portion 5 being made of a suitable material such as leather and adapted to have formed therein a plurality of slotted portions as at 7, 8 and 9. In order 30 to provide means for longitudinal adjustment, according to the length of the leg, as well as for the length of sock or stocking, a strap portion 10 made of suitable material such as elastic is formed having at one end 35 the sock attaching means 11 of the usual type and at the other end a loop portion 12 adapted to receive therein a removable stop

element 13. The looped end portion of the elastic 10 is adapted to extend through the upper opening 7 in the tab 5, then downward through the opening 8 and out through the opening 9, after which the stop element 13 is inserted in the loop and extends on each side of the elastic member 10 a sufficient distance to maintain the member 10 in a 50 fixed position, when the element 13 comes into contact with the pad 5 at the lower slit 9.

This invention provides a very efficient garter, simple and inexpensive of manufacture, which will function to adjust, not only circumferentially for the length of the leg, but also adjust for the length of the sock or stocking.

It is to be understood that alterations and 60 substitutions may be made in the disclosure as set forth in the drawing and the specifications within the scope of the claim without affecting the merits of this invention.

What I claim is:—

In an adjustable garter, a main body portion, means extending from the main body portion for adjustment as to the length consisting of a member slidably arranged on the main body portion, one end of the member being provided with a holding means and the other end with a detachable stop element adapted to hold the member in a fixed position when it contacts with the main body portion, the main body portion being provided with a plurality of openings arranged one above the other for receiving the member, the bottom opening being adapted to receive the member, which then passes through the top opening, then 70 through the middle opening and through the bottom opening again.

In testimony whereof I affix my signature.
LOUIS KEITH MORRISON.
